L. J. HARRISON

RUBBER HEEL

Filed Oct. 19, 1926

By Clarence O'Brien,
Attorney,

UNITED STATES PATENT OFFICE.

LOUIS J. HARRISON, OF DERBY, CONNECTICUT.

RUBBER HEEL.

Application filed October 19, 1926. Serial No. 142,663.

This invention relates to an improved rubber heel of the separable or detachable type.

Briefly, the invention has reference to a leather lift and a rubber lift fastened to the leather lift, the rubber lift being composed of main and supplemental sections, and there being novel means between the sections for permitting replacement and removal of the supplemental section, which, as is obvious, is the section which is subjected to the greatest wear.

My principal aim is to generally improve upon structures of this class by providing one of comparative simplicity and durability wherein the parts are novel and are associated in such a way as to render the structure practical and characteristic.

An important feature of the construction is the means for connecting the two sections of the rubber heel together, this embodying a slotted plate carried by one section, and a complementary plate carried by the other section and having headed studs 20 for reception in the slots in the first named plate, whereby to provide a readily separable connection between the two sections of the heel.

Other features and advantages will be apparent from the following description and drawing.

In the accompanying drawing forming a part of this application, and in which like numerals are employed to designate like parts throughout the same:

Figure 1 is a bottom plan view of a heel constructed in accordance with the invention.

Figure 2 is a side view of the same.

Figure 3 is a section taken approximately upon the plane of the line 3—3 of Figure 2.

Figure 4 is a transverse cross section taken approximately upon the plane of the line 4—4 of Figure 1.

Figure 5 is a top plan view of the removable supplemental section of the rubber lift, and

Figure 6 is an inside end view of the same.

Referring to the drawing in detail, it will be seen that the reference character 1 designates the leather ply or lift which is adapted to be secured to the shoe in any appropriate manner. The rubber lift is generally designated by the reference character 2 and as

before indicated comprises a main section 3 and a supplemental section 4. The main section is of an outline corresponding to the leather ply, and the latter is of the usual outline. It will be noted, however, that substantially one-half of the rear portion of the main section is cut away to provide a shoulder 5 which is inclined as shown in Figure 3 and which forms a relatively thin portion 6. The supplemental removable rubber section 4 is of a shape to fit accurately into the cut away area represented in Figure 3. Moreover, as shown in Figure 6 this section is bowed transversely to render it of cupped formation. In addition, it is provided on its inner side with a recess 7 in which a metal plate 8 is secured. This plate carries a pair of headed studs 9. The studs are proportioned in length with respect to the depth of the recess 7 to cause the heads to project above the inner surface of the rubber as shown in Figure 6. Formed in the thin portion 6 of the main section of the rubber is a recess to accommodate a complementary anchoring plate 10 of the configuration indicated in Figure 3. This plate is fastened by nails or the like 11. It is provided with a pair of elongated slots 12 at the rear ends of which are circular enlargements 13 adapted to permit passage of the heads on the studs.

In practice, the leather ply 1 is fastened to the shoe in any convenient manner and the shouldered portion or section of the rubber lift is secured thereto as represented in the drawing. Then the portion 4 is placed in position by inserting the heads of the studs 9 in the enlarged entrances 13, whereupon the shank portions of the studs are slid into the restricted portions of the slots. In this connection it will be noted from Figure 3 that the edge portions of the slots overhang the heads and provide a firm connection between the two sections of the rubber lift. Owing to the inherent resiliency and cupped shape of the section 4 as represented in Figure 6 it is obvious that the tendency of the same when flattened as indicated in Figure 4, is to resume its normal concavo-convex state, and hence it exerts an outward pull upon the studs, thus binding the heads of the same firmly against the anchoring plate 10. From practice it is known that the entire rubber heel does not wear equally and it is the portion represented by the reference character 4 which

is subjected to the greatest wear. Hence, by simply replacing this and having standardized connections, the expense of renewal of rubber heels will be comparatively small.

5 Moreover, it will be possible to renew the heel without requiring the services of a skilled repair man.

It is believed that by considering the description in connection with the drawings 10 a clear understanding of the invention will be had. Therefore, a more lengthy description is thought unnecessary.

While the preferred embodiment of the invention has been shown and described, it 15 is to be understood that minor changes coming within the field of invention claimed may be resorted to if desired.

Having thus described the invention, what I claim as new and desire to secure by Letters Patent is:—

As a new product of manufacture, a rub-

ber heel comprising a main section of conventional outline embodying a relatively thick portion and a relatively thin portion providing a shoulder at the juncture of said portions, said shoulder being inclined and disposed transversely across said section, a plate secured to the bottom face of said thin portion, said plate being provided with key-hole shaped slots, and said thin portion being provided with grooves in alignment with said slots, a renewable section of segmental configuration adapted to be placed against the bottom of said thin portion and to abut said shoulder, said renewable section being provided in its top with a recess, an attaching plate located in said recess and passed through said renewable section and carrying headed studs cooperable with the slots in said first named plate.

In testimony whereof I affix my signature.
LOUIS J. HARRISON.
